Primary Examiner — Brian N Vinson(74) *Attorney, Agent, or Firm* — Banner & Witcoff, Ltd.(57) **CLAIM**

The ornamental design for a clip-style light, as shown and described.

DESCRIPTION

FIG. 1 is a perspective view of a clip-style light showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a cross-sectional view taken through line 7-7 of FIG. 5.

The broken line disclosure in the views represents unclaimed portions of the light.
